Primary Examiner — John Windmuller*(74) Attorney, Agent, or Firm* — Terence P. O'BrienCLAIM

I claim the ornamental design for a racquet equipment bag, as shown and described.

DESCRIPTIONFIG. 1 is a top, side perspective view of a racquet equipment bag;
FIG. 2 is a first side view of the racquet equipment bag of FIG. 1;

FIG. 3 is a second side view of the racquet equipment bag of FIG. 1;

FIG. 4 is a top view of the racquet equipment bag of FIG. 1;
FIG. 5 is a bottom view of the racquet equipment bag of FIG. 1;FIG. 6 is a first end view of the racquet equipment bag of FIG. 1; and,
FIG. 7 is a second end view of the racquet equipment bag of FIG. 1.

The ornamental design that is claimed is shown in solid lines in the drawings: The broken (dashed) lines shown in FIGS. 1 through 7 are included for the purpose of illustrating environmental elements only and form no part of the claimed design.
